SIGNAL STORAGE DISCHARGE TUBES

George Baldwin Banks, Rawreth, England, assignor to English Electric Valve Company Limited, London, England, a British company

Application December 23, 1955, Serial No. 555,141

Claims priority, application Great Britain March 17, 1955

2 Claims. (Cl. 315—12)

This invention relates to signal storage discharge tubes, and more particularly to signal storing cathode ray tubes of the kind in which a cathode ray, modulated in accordance with signals to be stored, is caused to scan a target structure to store the signals in the form of charges thereon, the said target structure being subsequently scanned by a cathode ray to "read-off" the stored charges. A typical storage tube of this kind has two electron guns—a "writing" gun and a "reading" gun—directed towards a target structure which consists of a plate of glass or other suitable dielectric material sandwiched between a continuous conductive signal plate on the side remote from the two guns and a large number of discrete conductive electrodes on the side facing the said guns. When the discrete conductive electrodes are scanned by a signal modulated cathode ray from the "writing" gun, electrical charges corresponding to the signals are set up in the minute condensers which are in effect constituted by the target structure. If, subsequently, the discrete electrodes are scanned by the "reading" gun the stored signals are "read-off," the stored charges being of course thus "wiped off."

The invention is illustrated in and further explained in connection with the accompanying drawings in which

Fig. 1 is an explanatory graphical figure;

Fig. 2 is a schematic representation of one form of tube embodying the invention; and

Fig. 3 is a view of part of the target structure of the tube of Fig. 2.

It will readily be appreciated that in any particular known cathode ray tube as above described there are limits to the permissible voltages which can be allowed to be set up either across the glass plate in the target structure, or between the individual discrete electrodes on one side of that plate. Limitation of voltage across the glass plate, i. e. between the discrete electrodes on one side of the plate, and the signal plate on the other, presents no difficulties for the only requirement is that this voltage shall not exceed a value suited to the dielectric strength of the glass. In a typical case the permissible strength might be 30 kv. per mm., so that 6 kv. would be the maximum permissible voltage across a typical glass plate 0.2 mm. thick. The limitations of potential as between adjacent discrete electrodes are, however, much more severe. Consider the case of a glass plate able to withstand 30 kv. per mm. with adjacent discrete metallic electrodes on one side thereof spaced apart by 0.005 mm. Then the maximum permissible potential between adjacent discrete electrodes is only 150 volts if one considers merely the absolute spacing, but when it is remembered that the discrete electrodes present very sharp edges towards one another it will be seen that a voltage difference of this value could excite field emission at the edges and thus involve a risk of break down of glass at the electrode with consequent "tracking." In practice, therefore, the voltage between adjacent discrete electrodes cannot safely be allowed to exceed about two thirds of the voltage calculated on the basis of the strength

of the glass, i. e. for the typical example just given, a voltage of 100 is about as much as is safely allowable.

Further, as is well known, it is necessary, in the interests of efficiency, so to operate the "writing" gun of a known tube as above described, that the electrons therefrom reach the target with a velocity corresponding to a voltage above the point at which the curve connecting ratio of emitted secondary electrons to incident primary electrons crosses the unity ratio line for the second time. 5 In other words the "writing" gun has to be operated under conditions such that the number of secondaries released is smaller than the number of incident primaries, so that the negative charges are stored. On the other hand the "reading" gun must be so operated that the 10 electrons arrive at the target with a voltage above that corresponding to the first crossing of the unity ratio line, i. e. under conditions such that the number of secondary electrons released at the target exceeds the number of incident primaries so that the minute condensers of the 15 target structure are discharged and the discrete electrodes restored to a suitable datum potential determined by the potential of the normally provided internal conductive coating on the tube envelope. This will be clearer from Fig. 1 of the drawings which shows a typical characteristic curve connecting the ratio d of released secondary electrons to incident primary electrons (ordinates) with velocity of incident primaries (abscissae) in terms of voltage V . The horizontal line "X" is the line for unity ratio and it will be seen that the curve crosses this line in two 20 places, Y and Z, the former corresponding, in a typical case, to about 20 volts and the latter to about 5000 volts. Although the "reading" beam ray is operated at a voltage between Y and Z, the "writing" ray must, in practice, be operated at a point well beyond the point Z owing to 25 the small slope of the curve in the neighborhood of Z. There is therefore a real danger that, if the reading beam becomes for any reason inadequate or momentarily interrupted, some of the discrete electrodes will become charged to a voltage near that of the point Z of Fig. 1, and inter-electrode breakdown will occur. There seems to be no doubt that the spurious signals frequently experienced when "reading-off" known tubes as above described are due very largely to this cause. In addition such known tubes are very inefficient, particularly as 30 regards the "writing" process for which operation takes place with a secondary-primary electron ratio which is commonly not less than 0.9. There is considerable liability, moreover, for secondary electrons emitted at the target during both "reading" and "writing" to fall back on the target and thus produce spurious "shading" signals like those commonly experienced in television pick-up tubes of the so-called Iconoscope type. 35 The main defects of a known cathode ray storage tube as above described may be therefore summarised as follows:

- (1) They are liable to permanent break down at the target due to over-charging of the individual discrete electrodes.
- (2) They are liable to produce spurious signals due to 40 permanent or temporary break down of insulation between one discrete electrode and its neighbors.
- (3) They are inefficient both for "writing" and "reading" but especially the former, and
- (4) They are liable to produce spurious "shading" 45 signals due to the return of secondary electrons to the target structure.

The present invention seeks to avoid the above mentioned defects.

According to this invention a cathode ray storage tube 50 comprises a storage target structure composed of a plurality of minute condensers with a common electrode on one side of a dielectric plate and a plurality of separate

electrodes on the other, means for scanning said separate electrodes with a signal modulated "writing" cathode ray to charge the said condensers, means for scanning said separate electrodes with a "reading" cathode ray to collect the charges, and interposed means closely adjacent said separate electrodes for setting up a potential surface of one pre-determined value through which the "writing" ray reaches said electrodes and a potential surface of a widely different value through which the "reading" ray reaches said electrodes.

In a preferred embodiment there are two guns arranged to scan the target structure along adjacent separate paths and there is provided between each gun and the part of the target structure it scans a separate grid or similar electrode. Thus the ray from each gun can reach the target structure only through its appropriate interposed grid, and by applying different voltages to the two grids, the voltage excursion of the discrete electrode during "writing" and during "reading" can be positively limited as required. To quote practical figures the voltage of the grid across the path of the "writing" ray (hereinafter called the suppressor grid) might be 100 volts below earth, while the voltage on the other grid (hereinafter termed the collector grid) might be zero, i. e. earth potential in a case in which the signal plate was returned, through the usual output resistance, to earth and the normally provided metallic deposit on the inside of the tube envelope was connected to earth.

Fig. 2 of the accompanying drawings shows schematically one form of tube in accordance with the invention, and

Fig. 3 is a broken away face view of the target structure of the tube of Fig. 2.

Referring to Fig. 2, the tube therein shown has an evacuated envelope 1 with two necks 2, 3, at the end of each of which is an electron gun 4 or 5 of known construction and arrangement. In the main bulb 1 of the tube is a target structure consisting of a glass plate 6, for example, 0.2 mm. thick, with a continuous metal layer 7 constituting the signal plate on the rear side thereof and a large number of a discrete rectangular metallic electrodes 8 on the front or gun side thereof. These elements 6, 7 and 8 form a plurality of minute condensers. Each metallic electrode might, for example, be about 8 mm. long (the vertical dimension in Fig. 3) and about 0.06 mm. wide, and each might be separated from its neighbors by about 0.005 mm. It is of course impracticable to show dimensions such as these in a drawing, and no attempt has accordingly been made to indicate dimensions and proportions correctly in Figs. 2 and 3, which are, as stated, purely schematic. Each gun 4 or 5 is arranged to scan across the target in its own line, the two lines being spaced apart by a few mm. The scanning rays are indicated conventionally in the bulb 1 by arrow headed chain lines in Fig. 2. Thus for the sake of clarity in drawing, the two scanning rays are indicated as further apart in Fig. 2 and respectively nearer the tops and bottoms of the areas 8 than they would be in practice.

In the path of each scanning ray is a separate grid 9 or 10, each with its own external connection. The grid 9 is the suppressor grid and in the illustrated case in which the usual output resistance 11 from the signal plate 7 is returned to earth and the usual deposit 12 on the inside of the bulb 1 is also earthed, the suppressor grid 9 might be operated at minus 100 volts, and the other grid 10 (the collector grid) maintained at or about earth potential. These potentials are indicated in Fig. 2, but are of course given by way of practical example only. Each grid extends right across the target structure from left to right in Fig. 3, but only half way down so that one scanning line is under one grid, and the other under the other. In order not to increase the signal plate capacitance unduly, the height of this plate, i. e. the dimension which appears vertical in Figs. 2 and 3, is made less than

the over-all height of the electrodes 8. The grids should be of fine mesh and are close to the target surface, for example, 4 mils therefrom. With this arrangement the "writing" beam can be operated at or below the voltage of the point Z of Fig. 1,—never above it—while the "reading" beam can be operated very close to the condition which gives the maximum secondary-primary electron ratio. Secondary electrons released by the "writing" beam are unable to escape from the target because of the suppressor grid 9 and the discrete electrodes 8 thus acquire negative charges. This process can continue until the charge on said electrodes reduce to the potential of the suppressor grid after which further electrons can escape. Moreover, the suppressor grid is so close to the target that suppressed secondaries cannot spread and cause loss of resolution but are returned substantially to their points of origin at the target. Since, as stated, the "writing" gun operates below the point Z where the secondary-primary electrons ratio is unity or above, all the ray current is utilized and there is high "writing" efficiency. As will be apparent, the voltage excursion of the discrete electrodes 8 can be restricted to any desired range by adjustment of the suppressor and collector grid potentials and cannot exceed the difference between these two voltages. There is a great increase in ray efficiency for both "writing" and "reading" and since much lower primary ray currents are therefore required, the ray cross-sections can be reduced with consequent greatly improved resolution. Moreover, spurious "shading" signals and loss of resolution due to electron redistribution are largely eliminated.

I claim:

1. A cathode ray storage tube comprising a storage target structure composed of a plurality of minute condensers having a common electrode on one side of a dielectric plate and a plurality of separate electrodes on the other, means including a first electron gun for scanning said separate electrodes with a signal modulated "writing" cathode ray to charge the said condensers, means including a second electron gun for scanning said separate electrodes with a "reading" cathode ray to collect the charges, both said first electron gun and said second electron gun being disposed to the same side of said target structure as said separate electrodes, two separate fine mesh grid electrodes adjacent the target structure, each extending fully across said target structure in the direction of scanning and substantially half-way across in a direction perpendicular thereto in the plane of said target structure, one of said grid electrodes being interposed across the electron paths from said first electron gun to said target structure and the other of said grid electrodes being interposed across the electron paths between said second electron gun and said target structure, said two grid electrodes being closely adjacent said separate electrodes, means for applying potentials to said grid electrodes for setting up two different potential surfaces, the potential surface through which the "writing" ray reaches said electrodes having such predetermined value that secondary electrons from the target are suppressed and the potential surface, of a widely different value, through which the "reading" ray reaches said electrodes having such predetermined value that secondary emission from the target is assisted.

2. A tube as claimed in claim 1 wherein the grid electrodes are spaced from the adjacent target structure by a distance of the order of 4 mils.
